UNITED STATES PATENT OFFICE.

MEYER BAYUK, OF GLENSIDE, PENNSYLVANIA,

DISPLAY-CABINET.

,113,787.

Specification of Letters Patent. Patented Oct. 13, 1914.

Application filed May 1, 1914. Serial No. 835,751.

To all whom it may concern:

Be it known that I, MEYER BAYUK, a citizen of the United States, residing at Glenside, in the county of Montgomery, State of Pennsylvania, have invented a new and useful Display-Cabinet, of which the following is a specification.

My invention consists of a cabinet adapted for containing articles, more particularly 10 cigars, whereby they may be displayed to the best advantage for the purpose of inspection and purchase, while also protecting the articles from dust and dirt and improper handling.

It consists also of the addition to the body proper of the cabinet of a chamber for receiving the lid of the box in which the cigars or other articles are contained, so that the same is held in open condition, and the 20 trade-mark or brand thereon may be presented to view.

The invention is satisfactorily illustrated in the accompanying drawing, but the important instrumentalities thereof may be varied, and so it is to be understood that the invention is not limited to the specific details shown and described.

Figure 1 represents a perspective view of a display cabinet and humidor embodying 30 my invention. Fig. 2 represents a transverse vertical section thereof on the line $x-x$ Fig. 1. Fig. 3 represents a longitudinal vertical section on the line $y-y$ Fig. 2. Fig. 4 represents a side elevation of a detached portion 35 of the body of the device. Fig. 5 represents a vertical section of the upper portion of the device on an enlarged scale. Fig. 6 represents a plan view of the humidor, and a horizontal section of the portion of the leaf to 40 which it is attached.

Similar numerals of reference indicate corresponding parts in the figures.

Referring to the drawings, 1 designates a cabinet the main body of which is composed 45 of the transparent front 2, the transparent ends 3, the bottom 4, the transparent lid 5, and the leaf 6, which latter is hinged on its lower end to said bottom as at 7, whereby when said leaf is lowered it uncovers the rear 50 of said body and permits access to the inter-

rior thereof, and which when raised, covers and closes said rear.

Rising from the frame 8 of the transparent ends 3 at the rear portion thereof, is a stationary casing or chamber 9, which is 55 formed of the transparent front wall 10, and the top and side walls 11, it being noticed that the leaf 6 is extended upwardly above the main body of the cabinet as at 12, so as to close the rear of said chamber 9, but which 60 will be uncovered when said leaf is lowered and access is thereby had to the interior of said chamber.

The transparent lid 5 has its frame hinged at its rear end to the lower end of the frame 65 of the chamber 9 as at 13, whereby it may be raised so as to uncover the top of the box and permit access to the contents of the same, while when it is lowered, said contents are covered and protected from dust and im- 70 proper handling. The lower portions 14 of the ends of the box are formed of plates preferably of metal, whose upper ends are inturned forming the ledges 15 on which a box may be supported, said ledges being in- 75 clinied so that said box is tilted to the front, so that its contents which will be displayed through the transparent lid 5 may be pre- 80 sented to the best advantage for the purpose of inspection and purchase while the trans- 85 parent portions of the ends 3 of the body present the ends of the body to view expos- 90 ing the brand, color, term and other marks that may be thereon, it being noticed also that before the box is placed in the cabinet 95 the leaf is lowered and the lid of the box is raised, the box then being introduced into the main body of the cabinet, and its lid moved into the chamber 9 as an inclosure therefor, where it is held in raised or open 90 condition, and remains there, exhibiting to the front in comparative upright condition, the trade-mark or brand of the goods, noted on said lid, it being held in place by the leaf which is restored to its normal position and 95 held thereat by the catch 16 which is pivoted to the top wall 11 of the chamber 9 and adapted to overhang the top of the exten- 100 sion 12 of the leaf 6, but which when prop- erly turned releases said extension and con-

sequently the leaf permitting the latter to drop and so permit access to the body of the box and its lid. For temporarily holding the lid of the box in the casing or chamber 11 when the leaf 6 is open, the catch 16 is lowered so that it will overhang said lid and prevent it from dropping during the adjustment of the box in the cabinet, but when said leaf is to be closed, the catch is turned upwardly and the leaf raised to full extent, when its top will pass said catch. Then when the leaf is seated in its closed position, the catch is turned downwardly or drops when it again engages the leaf and prevents opening thereof. The stationary casing or chamber 11 has its front wall inclined forwardly from top to bottom, at which latter place it joins the butt of the hinge 13 of the lid 5 of the body of the cabinet. This widens the lower portion of said chamber to permit the lid of the box in open condition to be most conveniently inserted in the same, and allow it to be placed in inclined position back of the front wall of said chamber. This allows also the lid 5 of the body to be placed in inclined position on said wall to the front and rested thereagainst held in open position, while the contents of the body are uncovered and undergoing inspection and handling.

The lid 5 is provided with the lever or hand piece 17 for conveniently raising and lowering the same. On the inner face of the upper extension of the leaf 6 is the humidor or moistening device 18 which when the leaf is closed enters the chamber 9 and occupies the same, so as to impart humidity to the contents of the box, a feature of importance to cigars, it being noticed that the front wall of said chamber is inclined forwardly, so as to increase the capacity of said chamber, in order to properly receive said humidor as well as the lid of the box in its raised position, as most clearly shown in Fig. 2.

The humidor is composed of a box with perforated walls adapted to contain an absorbent and which is provided on its ends with tongues 19 which are fitted and sustained on ways 20 on the inner face of the leaf, thus adapting the box to be removed and replenished with water or other fluid.

The body of the cabinet is preferably of the form of a trapezium, so as to assist in displaying the box or its contents to the best advantage in its inclined position in said cabinet.

Having thus described my invention what I claim as new and desire to secure by Letters Patent, is:—

1. A cabinet composed of a body, a transparent lid therefor, a chamber rising stationarily from the rear portion of the frame of said body, said lid being hinged to the

base of said chamber at the front thereof, 65 the front face of said chamber being transparent, the rears of said body and chamber being open in communication with each other, and a leaf extending from the bottom of the body to the top of the chamber forming a common closure for the open rears of 70 said chamber and body, said front face extending inclined forwardly from the top of said chamber to the bottom thereof.

2. In a cabinet, a box-receiving and supporting body having a transparent lid adapted to be opened, a stationary lid-receiving and supporting chamber rising from the frame of said body, the rears of said chamber and body being open in communication with each other, and a member adapted to form a closure for said open rears of the body and chamber.

3. In a cabinet, a box-receiving body having a transparent lid, and means for supporting a box inclined in said body, a stationary chamber rising from the frame of said body at the rear thereof forming an enclosure for the lid of the box in open condition, the front face of said chamber 85 being transparent and inclined, the rears of said chamber and body being open in communication with each other, a leaf adapted to form a common closure for the open rears of said body and chamber, and a catch 90 adapted to engage separately with the lid of the box and with said leaf in closed position.

4. A cabinet of the character stated composed of a body adapted to receive a box, 100 a transparent movable cover for said box, a lid inclosing chamber rising stationarily from said body, the front of said chamber being transparent and in inclined condition, the side of the frame of the box being partly 105 transparent to expose the side of the box and partly formed of plates of non-transparent material with inturned inclined ledges adapted to support said box in the body in inclined position, said chamber and 110 body being open at their rears and in communication, and a leaf adapted to close said rear openings common to both.

5. A cabinet for a body and its lid composed of a box-receiving body, means for 115 supporting the box in inclined position therein, a transparent lid for said body, a stationary lid receiving chamber rising from the rear portion of said body, the front wall of said chamber being transparent, the rears 120 of said chamber and body being open in communication with each other, and a closing leaf for said open rears common to both, said transparent front wall of said chamber being inclined from its top forwardly to its 125 place of connection with the rear portion of said body.

6. A cabinet composed of a box-receiving

body, a transparent lid therefor adapted to expose the box, a lid-receiving and supporting chamber rising stationarily from the rear portion of the frame of said body, the 5 front face of said chamber being transparent adapted to expose said lid, the rears of said body and chamber being open in communica-

tion with each other, and a leaf connectible with the frame at said open rears adapted to form a closure for the latter.

MEYER BAYUK.
